UNITED STATES PATENT OFFICE.

FAIRFAX HENRY WHEELAN, OF SANTA BARBARA, CALIFORNIA.

SEPARATOR.

SPECIFICATION forming part of Letters Patent No. 474,930, dated May 17, 1892.

Application filed April 16, 1891. Serial No. 389,218. (No model.)

To all whom it may concern:

Be it known that I, FAIRFAX HENRY WHEELAN, a citizen of the United States, residing at Santa Barbara, Santa Barbara county, State 5 of California, have invented an Improvement in Separators; and I hereby declare the following to be a full, clear, and exact description of the same.

My invention relates to the art of separation and to the class of machines and apparatus therefor.

It consists in a mode or method of separating materials composed of particles of different sizes by carrying the material upon a suitable moving surface toward a succession of graduated openings and drawing them by and upon said surface through said openings as their sizes will permit.

My invention also consists in a mode or 20 method of separating materials composed of particles of different sizes and having a greater length and breadth than thickness by carrying the material upon a suitable moving surface toward a succession of graduated 15 openings, presenting the particles edgewise to said openings, and drawing them by and upon said surface through said openings as their different thicknesses will permit.

It further consists in a mode or method of 30 separating material composed of particles of different sizes and having a greater length and breadth than thickness by carrying the material upon a suitable moving surface toward a succession of graduated openings, presenting the particles edgewise to said openings, drawing them by and upon said surface through said openings as their different thicknesses will permit, and finally keeping separated the different-sized particles which pass 35 through the said graduated openings.

It also consists in the novel construction of 40 machine or apparatus by which my mode or method is carried out, as I shall hereinafter fully describe, and specifically point out in 45 the claims.

The general object of my invention is to provide for the separation of material particles composed of different sizes.

The particular object is to separate the particles of dirt and the imperfect specimens 50 from grains and seeds having greater length

and breadth than thickness—such, for example, as Lima beans.

In the accompanying drawings, to which reference is made, and in which Figure 1 is a plan and Fig. 2 is a vertical section, I have shown a novel apparatus adapted to carry out my mode or method of separation. Fig. 3 is a detail showing the spouts and troughs.

A is a frame or stand in which is mounted 60 suitably a vertical shaft B, adapted to be driven by means of suitable power connections, such as the belt and pulley C. Upon this shaft is mounted a horizontal bed or table D, the surface of which may be of any 65 suitable material, smooth or slightly roughened, or more roughened—such, for example, as wire-cloth. In the center of this table is a feed-chamber d, into which the material is fed from a hopper E above.

Suitably secured above the table D is the series of stationary guides. These guides are in sets of three and are around the entire table. The first guide of each set is designated by F, and its inner end is tangential to the 75 circumference of the feed-chamber d and is in communication therewith. From its inner end outwardly a short distance the under edge of the guide F is cut away, leaving an opening f under it, and from the outer end of 80 this opening the guide F is again cut away, leaving another opening f', which is wider or higher than the opening f, and from there out the guide is solid and comes down close to the surface of the table. Leading off from 85 the inner end of the opening f and just behind the guide F is a guide G, which extends outwardly to any desired distance—as, for example, to the edge of the table. From the inner end of the opening f' extends a middle 90 guide H, parallel with the guide G and extending to the edge of the table. These guides F, G, and H constitute one set, and there are similar sets of guides all around the table. At the outer ends of these guides are secured 95 spouts F', G', and H', which have their lower ends in communication with the three separated troughs F², G², and H².

Secured to the table D is an arm I, having scrapers i extending down into the troughs, 100 and at different portions of the trough are openings J, by which their contents may

be discharged when pushed to them by the scrapers.

The general mode or method of separation carried out by this apparatus is as follows:

- 5 The material to be separated consists of particles of different sizes. It is fed from the hopper into the feed-chamber *d*. As the table *D* revolves the material passes outwardly by draft along the inner ends of the guides *F*.
 10 As it moves along the guides *F* those particles which are small enough will be carried or drawn by the table (to the surface of which they cling) through the openings *f* in the guides *F*, while the larger particles will not pass through said openings. The smaller particles which have been drawn through the openings *f* meet with the guides *G*, and by draft are carried outwardly along said guides to the spouts *G'*, and are by them delivered into the trough *G²*. Larger particles passing by the openings *f* will be drawn by the surface of the table through the openings *f'*, and, meeting with the guides *H*, will be by draft conducted outwardly to the spouts *H'*, by which they will be discharged into the trough *H²*. Those particles which are too large to pass through the openings *f'* will be conducted outwardly by the guides *F* into the spouts *F'* and thence into the trough *F²*. In these troughs the separated particles can be collected in any suitable manner, as by being scraped along to their several openings. It is obvious that the basis of my separation is embodied in the description heretofore made and that material
 35 composed of particles of different sizes is separated by being drawn toward a succession of graduated openings, through which the particles pass according to their sizes. This mode or method differs from the ordinary method
 40 of screening, in that the material is positively drawn through the openings to which it is previously positively directed. Now the particular material to which my mode or method is applicable is a material composed of particles having greater length and breadth than thickness. Take, for example, Lima beans. With many seeds and grains, especially with Lima beans, there are found mixed split beans and particles of dirt. The shape of a Lima
 45 bean is well known, its length and breadth being greatly disproportionate to its thickness. In operation upon this apparatus the split beans, being thin, pass through the openings *f*. The perfect beans, failing to pass said
 50 openings by reason of their greater thickness, pass through the openings *f'*, while the particles of dirt, being, as a rule, very much thicker than the beans, though not so long or so wide, will not pass through either of the
 55 openings *f* or *f'*, but will be conducted along by the guides *F* to their outer end. Such particles of dirt as will pass through the openings *f'* by reason of being thin are very much smaller otherwise than the perfect beans, and
 60 therefore they can be readily screened away from the beans afterward by the use of an ordinary screen, through which they will fall,
 65

while the beans will not, or such small dirt can be screened out on the table itself; but the greater part of the dirt particles will not 70 pass through the openings *f'*, as they are too thick.

In screening operations there are two courses to pursue—first, to make the screen with a mesh large enough to let the beans fall 75 through and keep the dirt on the screen; but on account of the peculiar shape of the beans these openings would have to be very large, and consequently very large pieces of dirt would pass through the meshes with the beans. 80 The second course is to make the openings small enough to allow the particles of dirt to pass and retain the beans; but such openings would only allow the small particles of dirt to pass, because the shape of the particles 85 of dirt is such that the larger pieces would require openings large enough to let the beans fall through. We have therefore to work upon the principle of the different thicknesses between the beans and the particles of dirt, 90 and an ordinary screen could not be successfully used to carry out this principle. On the contrary, a mode or method which draws the beans positively through graduated openings, 95 said beans presenting their thickness to the openings, is practicable and will effect the result.

Having thus described my invention, what I claim as new, and desire to secure by Letters Patent, is—

1. An apparatus for separating materials composed of particles of different sizes, consisting of a moving surface upon which the material is fed, and guides above said surface having graduated openings to permit 105 the passage as the material is drawn through them by the moving surface of different particles, according to their several sizes, substantially as herein described.

2. An apparatus for separating materials composed of particles of different sizes, consisting of a moving surface upon which the material is fed, guides above said surface having graduated openings to permit the passage as the material is drawn through them 115 by the moving surface of different particles, according to their several sizes, and a separate guide behind and in communication with each opening to receive and maintain separate the different-sized particles, substantially 120 as herein described.

3. An apparatus for separating materials composed of particles of different sizes, consisting of the rotating table and the series of guides above said table in sets of three, composed of the guides *F*, having the graduated openings *f f'*, the guides *G* in communication with the openings *f*, and the guides *H* in communication with the openings *f'*, substantially 125 as herein described.

4. An apparatus for separating materials composed of particles of different sizes, consisting of the rotating table having the central feed-chamber, the sets of guides, each 130

composed of the guides F, having the graduated openings f and f' and the guides G and H in communication with said openings, the spouts at the ends of the guides, and the 5 troughs in communication with said spouts, substantially as herein described.

5. An apparatus for separating materials composed of particles of different sizes, consisting of the rotating table having the central feed-chamber, the sets of guides, each composed of the guides F, having the graduated openings f and f', and the guides G and

H in communication with said openings, the spouts at the ends of the guides, the troughs in communication with said spouts, and the 15 scrapers connected with the rotating table and operating in the troughs, substantially as herein described.

In witness whereof I have hereunto set my hand.

FAIRFAX HENRY WHEELAN.
